UNITED STATES PATENT OFFICE.

JOHN WOJCIK, OF CHICAGO, ILLINOIS.

DESIGN FOR A PICTURE.

47,979.

Specification for Design. Patented Oct. 12, 1915.

Application filed June 18, 1915. Serial No. 34,967. Term of patent 7 years.

To all whom it may concern:

Be it known that I, JOHN WOJCIK, a citizen of the United States, residing at Chicago, in the county of Cook and State of Illinois, have invented a new, original, and ornamental Design for Pictures, of which the following is a specification, reference being had to the accompanying drawing, forming a part thereof.

I claim:

The ornamental design for a picture, as shown.

JOHN WOJCIK.

Witnesses:

ANTONINA MALINOWSKA,
EDWARD J. STRZYZOWSKI.
